CLAIM

The ornamental design for an autonomous vehicle headlamp, as shown and described.

DESCRIPTION

The present application is related to copending application Ser. No. 29/491,722, entitled Autonomous Vehicle Overall Exterior; to application Ser. No. 29/491,723, entitled Autonomous Vehicle Door; to application Ser. No. 29/491,717, entitled Tire Rim; to application Ser. No. 29/491,730, entitled Autonomous Vehicle Taillamp; to application Ser. No. 29/491,726, entitled Autonomous Vehicle Wing Assembly; and to application Ser. No. 29/491,727, entitled Autonomous Vehicle Rear Vent/Reflector, each of which is filed concurrently herewith, the entire disclosures of which are incorporated by reference herein.

FIG. 1 is a front perspective view of an autonomous vehicle headlamp according to our design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top elevation view thereof; and,

FIG. 7 is a bottom elevation view thereof.

The embodiment shown in FIGS. 1 through 7 illustrates the autonomous vehicle headlamp arranged for use on a right side of a vehicle. Another embodiment encompassed by this design includes the autonomous vehicle headlamp on a left side of the vehicle, wherein such embodiment is a mirror image of the design disclosed in FIGS. 1 through 7 and therefore is not separately illustrated.

The broken lines shown in the drawings illustrate environmental subject matter which forms no part of the claimed design.
